UNITED STATES PATENT OFFICE.

THOMAS MARRIN, OF OIL CITY, PENNSYLVANIA.

APPARATUS FOR REFINING PETROLEUM AND TAR.

SPECIFICATION forming part of Letters Patent No. 243,930, dated July 5, 1881.

Application filed May 14, 1880. (No model.)

To all whom it may concern:

Be it known that I, THOMAS MARRIN, of Oil City, in the county of Venango and State of Pennsylvania, have invented new and useful Improvements in Apparatus for Refining Petroleum and Tar; and I do hereby declare that the following is a full, clear, and exact description of the invention, which will enable others skilled in the art to which it appertains to make and use the same, reference being had to the accompanying drawings, and to letters of reference marked thereon, which form a part of this specification, in which drawings—

Figure 1 represents a perspective view of the apparatus with the condensing-tank in section. Fig. 2 represents a section of the benzine and gas tank with a steam-coil therein. Fig. 3 represents a section of a number of drums in a condenser. Fig. 4 represents a section of a fire-escape valve.

Similar letters of reference in the several figures denote like parts.

Heretofore the methods employed for refining have been worked at great disadvantages and some loss of the products, owing to the imperfect construction of the apparatus employed. The various grades of the distillate have to pass through several mechanical devices after leaving the stills—such as the steaming apparatus and spraying-house—and have to be manipulated considerably before they are ready for the market. The residuum or tar remaining in the stills after the illuminating-oil has all passed over is redistilled several times before arriving at the proper degree for lubricants and paraffine for making wax and other products, thus involving a great loss of time and expense by the ordinary apparatus and methods employed. With my improved apparatus the different grades of oil are run at one distillation without employing other apparatus for a separate treatment, and at a certain stage of the process the gravities work somewhat automatically by the arrangement of the tubes or pipes located in the separator, to be hereinafter more fully described.

In the distillation of the tar the entire contents of the stills can be run without redistilling, which cannot be accomplished by the ordinary process.

My invention consists in a separator composed of a tank and siphon-pipes, immersed therein, and having tail-pipes at their lower end, in combination with vertical pipes projecting above, an elevated pipe uniting the latter, 55 and a pipe leading to a benzine-tank, with other details of construction, which will be first described in connection with the drawings, and then the invention will be still more clearly pointed out in the claims.

In the drawings, A indicates the retort or still, which is provided with a number of pipes, a, which connect with a number of vertical pipes, C, arranged in pairs for receiving the gases and condensed vapors. Connecting with 65 each pair of these vertical pipes C are a number of distributing-pipes, E, which are connected about centrally at e and partially immersed in the water of the condenser. These distributing-pipes extend somewhat above the 70 pipes C and connect with the succeeding pair of vertical pipes at e', and in the same way with every pair of pipes C, and finally terminate in the gas or vapor pipe D'. There is also another vapor-pipe, D, elevated considerably above the other pipes, and adapted for the lightest vapors, so as not to crowd the other pipes when the distillate comes over too fast, as shown at Figs. 1 and 3. All of the 75 above-mentioned pipes and connections constitute my separator. These vertical pipes C are also provided with short horizontal pipes C', for relieving the pressure on the still when the distillation is too rapid, the gas which should have passed to the next pair of pipes 80 85 being partly condensed in forcing through the liquid in the first pair of pipes.

Connecting at the lowermost part of each pair of vertical pipes C are tail-pipes 1, 2, 3, 4, 5, 6, and 7. Said tail-pipes are provided 90 with cocks 8, 9, 10, 11, 12, 13, and 14, which are designed to close the flow of oil or distillate to the small receiving-tanks 21, 22, 23, 24, 25, and 26 at certain stages of the distillation, and opening the cocks 15, 16, 17, 18, 19, 95 and 20, secured to the pipes I and I', allow the distillate to flow into the general tank J, and also into the general tank for light oils, (not shown in the drawings,) communicating with pipe I'. 100

The object of having the pipes C and E project above the condenser F, as shown at e^3 , is to allow the vapors which are not condensed in the first pair of pipes to arise and not condense too soon, but pass into the succeeding pair of pipes, and so on, continuing to the termination of the series.

Secured to the vapor-pipe D' is a vapor or fire escape valve, h , a check-valve, i , and also 10 a cock, j . There is also another pipe, D², provided with a cock, j' , and connecting with a tank. (Not shown in the drawings.) The object of the check-valve i is to prevent fire from running back or communicating with the stills, 15 as the back-pressure of the gas will close the check-valve, owing to the sudden expansion of said gas by the fire, and the fire-escape valve h , which opens into the atmosphere, (shown at Fig. 4,) would allow the flames to 20 appear, thus notifying the employés, or the gas-whistle h' , on the gas-tank 27, would also notify that something was wrong, when the cock j would be closed and the cock j' opened, thus allowing the gases to communicate with 25 another tank, and thus prevent the gases from escaping and causing a general conflagration.

The tank 27, for holding gas and benzine, is provided with a pressure-valve, k , and a gas-whistle, h' , which are to notify the employés 30 when the tank is full, when the cock l is opened, and the surplus gas is drawn through pipe L into the pump M, from whence it is forced through pipe L' into the gas-holder N.

The gas-holder is of the ordinary construction, such as used in common gas-works. Connecting with the gas-holder N and the tank 27 are pipes $m\ m'$, which connect with feed-pipes $n\ n'$, for feeding the furnaces under the stills. On the bottom of the benzine-tank 27 is a steam-40 coil, O, (shown at Fig. 2,) for vaporizing the light products for feeding the furnaces.

At Fig. 3 the separator is composed of drums C², which have divisions or partitions e , for holding the gases in abeyance until partly condensed, the remaining gases passing to the opposite side of said partition and into the next drum and operating in a similar way to the separator shown at Fig. 1, but with not quite as good results.

50 In operating my improved apparatus, the still A is charged with crude oil, all the cocks being closed except the benzine-cock 14 and the gas-cock j . (Said cock j is always open except in case of fire, as previously described.) After the charge has run somewhat cocks 13, 12, and 11 are opened, allowing the distillate to flow into the tanks 26, 25, and 24. As the gravities become heavier the cocks 10, 9, and 8 are opened, thus allowing different gravities 60 to flow into separate tanks, the heavier oils flowing into tank 21, and so on to the lightest, which would be 26, then dropping 26 to 25 tank, and back again to 22 and 21, until the distillate is entirely run. By "entirely run" 65 I mean that the tar can be brought over with

the oils, and thus running the stills entirely dry. If preferable, the distillate can be discontinued at any stage in the process, which can be ascertained by the gage-cocks p , located in the still A. When the cocks are all 70 opened and the gravities become somewhat regular, they become automatically self-regulating, owing to the peculiar construction of the separator. It frequently happens that the fires are too hot or not hot enough, when 75 the gravities will vary, and variation would be detrimental to the quality of the distillate.

With my improved apparatus the distillate is self-regulating at certain stages of the process, which is occasioned by the arrangements 80 of the pipes C, E, and e , which constitute the separator—that is, as the gases come over into the first pair of pipes they partly condense, if the vapors are heavy enough, and pass out the tail-pipe 1, the uncondensed vapors pass 85 upward and become more volatile as they enter the unimmersed parts e^3 , which allow them to flow to the next succeeding pair of pipes, 6, when the gases are again condensed and flow into the tail-pipe 2, the remaining uncondensed vapors entering the pipe E to the next pair, the distillate becoming lighter in gravity as it approaches the gas-pipe D', as previously stated, and finally terminates from tank 26, running back to tanks 22 and 21, when the 90 oil is the heaviest and the charge is all run.

I am aware that the separators of petroleum-refineries have been provided with coiled pipes immersed in cooling-liquid; that a series of tanks have been used to receive the distillate 100 of different gravities, and that the light products of the gas have been burned under the still or stored in tanks. Therefore, I do not claim any of the old devices, broadly; but

That which I claim as new, and desire to secure by Letters Patent, is—

1. In a refinery for distilling petroleum or its residuum, a separator composed of a tank, F, siphon-pipes C, immersed in cooling-liquid, vertical pipes E, above said liquid, and elevated pipes uniting the latter with pipe D, and pipe D', connected with benzine-tank, substantially as shown and described.

2. In a refinery, the combination of the tank F, siphon-pipes C, immersed in cooling-liquid, 115 vertical pipes E, above said tank, with tail-pipes 1 to 6, connected with the lower bends of siphon-pipes C, condensing-troughs H, and tanks 21 to 26, all arranged substantially as shown and described.

3. In a refinery, the combination of the tank F, siphon-pipes C, having their lower end immersed in liquid of said tank, and their upper end projecting above, with pipe D elevated above and uniting said pipes, pipe D', 125 its check-valve i , vapor-escape valve h , and benzine-tank having steam-pipe coil, substantially as and for the purpose described.

4. The combination, in a refinery, of a tank, F, a series of siphon-pipes having their lower 130

end immersed in a cooling-liquid in said tank, an elevated connecting-pipe uniting the upper end or longest leg of the siphons, and pipe D' with the benzine-tank 27, steam-coil O there-
5 in, and gas-holder N, substantially as shown and described.

In testimony that I claim the foregoing as

my own I affix my signature in presence of two witnesses.

THOMAS MARRIN.
